INVENTOR.

LEWIS E. RISING

BY

William E. Baff. ATTORNEY.

UNITED STATES PATENT OFFICE.

LEWIS E. RISING, OF WORCESTER, MASSACHUSETTS.

TOY ARROW-SLING.

1,358,674.

Specification of Letters Patent.

Patented Nov. 9, 1920.

Application filed October 1, 1919. Serial No. 327,795.

To all whom it may concern:

Be it known that I, LEWIS E. RISING, a citizen of the United States of America, and a resident of the city of Worcester, in the county of Worcester and State of Massachusetts, have invented certain new and useful Improvements in Toy Arrow-Slings, of which the following is a specification.

This invention relates to improvements in toy impulsion means for impelling arrows.

The object of this invention is to provide an exceedingly simple form of device for the above specified purpose, which can be made inexpensively and will be durable and effective.

In the drawings wherein similar reference characters designate similar parts throughout the several views,

20 Figure 1 is a top plan view of one form of my invention,

Fig. 2 is a side elevation thereof,

Fig. 3 is a front elevation thereof,

25 Fig. 4 is a rear end elevation of a modified form of spring,

Fig. 5 is a rear end elevation of my preferred spring,

Fig. 6 is a top plan view of a modification,

30 Fig. 7 is a vertical sectional elevation of the first form of my invention,

Fig. 8 is a modification of the spring holding means, and

Fig. 9 is an end elevation of said modification.

In the drawings which are merely illustrative of my invention 1 designates a suitable handle made of any shape and of any material and 2 designates an eye having screw 2', being inserted into said handle 1, the eye having the free terminal 3 which provides a slit. I preferably mount a pair of expansible springs upon the eye, and, as one manner of attaching the springs thereto, I employ a plurality of coiled springs, the first 10 of which series is first inserted into the slit at 3 so as to run on the wire eye 2 until positioned on the base 4 as shown in Fig. 2, in the same manner in which a key is usually inserted on a key ring. The hook 7 of spring 6 is next slipped on the eye 2 in the same manner so as to engage the spring 10, after which another coiled spring 11 is slipped on the eye 2 to engage the hook 7, after which the hook terminal 8 of the other expansible spring

5 is inserted on the eye 2. Lastly the coiled spring 12 is inserted in the same manner so as to keep all the springs 10, 11, and 12 in position. By means of this construction 60 it will readily be seen that the two hooks 7 and 8 are located between springs constituting cushioning means and are held apart the proper distance by these same springs. The two springs 5 and 6 are branches of 65 one main spring, said branches being connected by the integral portion 9 at their inner planes as illustrated at Fig. 5. The shank 19 of the arrow will have the usual recess of desired form adapted to engage 70 against the portion 9, while the head or barb 20 is secured securely upon this shank. Instead of providing an integral spring structure it may be found desirable to provide two separate springs 5 and 6 and to 75 connect them by a link 9' formed with hook terminals 13, 14 at its opposite ends adapted to engage the eye 2. This feature is one particularly illustrated in Figs. 4 and 6. In this form of my invention the 80 convolutions 5, 6 are bent to provide the offsets 15, 16 as may be found necessary to connect the hook terminals 13, 14.

Another modification of my invention consists in providing a different means of 85 securing the springs upon the eye 2. The eye 2 is formed at diametrically opposite points with notches or nicks 17 as shown at Figs. 8, 9, the hooks 18, 17' of the springs 5, 6 being sprung into these recesses as 90 shown in Fig. 8. The form of spring support shown in Fig. 3 is preferably however shown because of the fact that the same provides a spring cushion for the springs 5 and 6 adapted to cushion the jar and shock occasioned by the relaxation of the springs 5 and 6 after they shall have been expanded. It will be found in practice that this sling for arrows provides a powerful means of impelling missiles especially arrows over great 100 distances and will prove a satisfactory means of exercise for youngsters and afford a means of testing the skill and accuracy of arrow shots aimed at targets. The arrow shank 19 may be of metal or wood and is 105 adapted to be guided in the opening 20 of the handle 1, the latter affording a secure hand hold for steadyng the instrument in the hands of the archer which will be found to give the archer a more accurate aim for 110 sending the arrow on a straight course.

Numerous modifications may be resorted

to in practice without departing in principle from the details of construction disclosed herein.

What I desire to protect and claim is:—

5 1. An arrow sling comprising a handle having a flat eye constituting an arrow guide, and a spring arrow impelling device having its ends connected at opposite sides of the eye, said eye having diametrically 10 opposite provisions in its own plane for receiving the ends of said arrow impelling device.

15 2. A device as described consisting of a handle, an arrow guide member secured thereupon, a spring sling, and springs coiled on said member and holding said sling in place thereupon.

20 3. A device as described, consisting of a handle, an arrow guide secured thereupon, a series of coiled springs engaging said guide, and a spring sling having hooks secured between said coiled springs.

25 4. A device as described consisting of a handle, a ring carried by said handle at one end, a series of springs fitting around said ring, and a spring sling carrying a pair of springs having hooks mounted between said springs.

30 5. A spring sling made from a single length of spring wire bent to provide two coiled springs arranged in parallelism and having a central integral wire providing a finger hold.

35 6. A device for the purpose described comprising a spring sling, a handle, means for securing said sling upon said handle, and

means extending above and below the sling on said handle for cushioning the action of said sling.

7. A device for the purpose described comprising a spring sling, and means for holding said sling yieldingly upon said handle to cushion any vertical motion of the sling.

8. A device for the purpose described comprising a handle, an eye bolt having a screw tapped into said handle, said eye bolt providing an arrow guide, and a sling having expandable portions on opposite sides of the handle secured separately to said eye-bolt.

9. A device for the purpose described comprising a handle, a ring projecting forwardly thereof and providing an arrow guide, a series of springs coiled around said ring and out of contact with one another, and a pair of springs having hooks also coiled around said ring and bearing against said springs.

10. In a device for the purpose described, a split ring, a pair of springs coiled upon said ring alongside each other, hook elements coiled onto said ring and bearing against said pair of springs, another spring coiled around said ring and holding said hook elements in place, and a sling secured to said hook elements.

In witness whereof he has hereunto set his hand and affixed his seal this twenty seventh day of September, 1919.

LEWIS E. RISING. [L.S.]
